UNITED STATES PATENT OFFICE.

OLIVER E. VANASDALE, OF YORK, PENNSYLVANIA.

TROLLEY-HARP.

1,331,540.

Specification of Letters Patent. Patented Feb. 24, 1920.

Application filed February 1, 1919. Serial No. 274,547.

To all whom it may concern:

Be it known that I, OLIVER E. VANASDALE, a citizen of the United States, residing at York, in the county of York and State of Pennsylvania, have invented a new and useful Trolley-Harp, of which the following is a specification.

This invention relates to trolley wheels, and more particularly to the trolley-harp, in which the trolley wheel proper is mounted for rotary movement.

The object is to provide a trolley-harp in which the wheel is securely held in position by simple means requiring but a single operation to secure the same in locked position and prevent its accidental displacement.

Another object is to provide locking means for the coacting parts of a trolley-harp, which will effectually prevent any longitudinal or other movement of the axle which, as is customary, must be clamped securely to prevent any movement whatsoever, the wheel proper revolving around said axle in its travel along the line wire.

A full and complete understanding of the invention may be obtained from a consideration of the following detailed description taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

In the drawing, in which like reference characters designate corresponding parts throughout the several figures:

Figure 1 is a side elevation of a trolley-harp having the improvements incorporated therein;

Fig. 2 is a plan view thereof;

Fig. 3 is a fragmentary perspective view showing the novel features of the invention in separated position;

Fig. 4 is a detail longitudinal sectional view thereof;

Fig. 5 is a detail side view of the adjustable locking member;

Fig. 6 is a bottom plan view thereof; and

Fig. 7 is a detail sectional view taken on the line 7—7 of Fig. 4.

55 The frequent slipping of trolley wheels

from their proper contact with the line wires of electric railroads is not only a source of great annoyance to passengers by causing frequent delays, but in the aggregate amounts to a considerable expense to the operating companies, by reason of the fact that in the majority of cases the trolley is damaged to a greater or less degree by coming forcibly into contact with the cross arms supporting the trolley wire, and being so bent or distorted as to necessitate their repair or the replacement of parts in order to take up lost motion or slack and to prevent rattling. This disadvantage is generally present in the use of trolley-harps of ordinary construction.

The present invention comprises a trolley-harp having coacting clamping members 1 and 2, respectively, adapted to hold securely against rotation an axle 3, on which is mounted a trolley-wheel 4. The clamping members 1 and 2 are each substantially U-shaped, and are hinged together at their outer terminals, as at 5, to permit a relative swinging movement. Adjacent to the hinge-pintles, the clamping members are each provided with coacting bearings 6 formed of substantially semi-circular seats in the abutting faces of the members 1 and 2, and each having an inwardly directed annular flange 7 adapted to overhang the ends of the axle 3 and prevent any longitudinal movement of the same within the bearings 6. The usual guards 8 are formed on the member 2, which constitutes the upper member, and act to prevent the trolley-wire from becoming lodged between the wheel 4 and the trolley-harp in the event of the accidental slipping of the wheel from the trolley wire.

The lower clamping member 1 is provided with a tubular extension 9 adapted to receive the end of the trolley pole 10 and to be secured thereto by a rivet 11 or in any other desirable manner. The tubular extension is also provided with a reduced portion upon its under side having a perforation 12, the latter constituting an eye for the reception of a cord or rope 13, indicated in dotted lines in Fig. 1 of the drawing, and used for the purpose of pulling down the trolley when desired, in the ordinary manner.

The upper surfaces of the arms constituting the lower clamping member 1 are in alinement with the axis of the hinge-pintle at the outer ends thereof, and also with

the longitudinal axis of the tubular extension 9, and thus provide an upstanding wall or shoulder 14 of arcuate formation, as shown in Fig. 2, and adapted to receive the connecting portion of the upper clamping member which is arcuately formed to snugly fit therein, and which assumes substantially the same relation to the tubular extension as does its integrally connected lower clamping member 1.

The upper surface of the tubular extension 9, adjacent to its point of contact with the connecting portion of the clamping member 2, is provided with the major portion of a circular socket 15, the remaining portion 16 of said socket being formed in the adjacent clamping member 2, the projecting bottom wall 17, thus provided, having a rib 18 formed thereon extending 20 radially to the axis of the socket and longitudinally of the tubular extension 9. The upstanding wall or shoulder 14 and the lower edge of the upper clamping member 2 are correspondingly rounded as indicated 25 at 19 and 20, respectively, and at the center of the socket, there is provided a threaded bore 21 extending entirely through the lower clamping member 1 and communicating with a recess 22 formed on the under 30 side thereof.

A locking member 23, in the form of a circular turn-button of a diameter nearly equal to the diameter of the socket 15 is adapted to fit within said socket and to lie 35 substantially flush with the upper surface of the upper clamping member 2, the said turn-button or locking member 23 having an arcuate cutaway portion 24 formed at one side thereof and cut on a like radius to 40 the rear edge of the connecting portion of the upper clamping member 2, as will be seen in Fig. 2.

The locking member 23 is provided with a centrally located perforation 25 registering with the threaded bore 21 of the lower member, and a suitable screw 26 is adapted to pass therethrough and into the said bore, to swivel the button or locking member within the socket, the screw extending 50 slightly into the recess 22 and being upset as at 27, indicated in Fig. 4 of the drawing, in order to prevent its accidental dislodgment.

The underside of the turn-button or locking member 23 is formed with a cam surface (see Fig. 5) and is provided with a series of radially-disposed teeth 28 extending from the thickest to the thinnest portion of said member. The thin portion of the locking member, caused by the said cam formation on the underside thereof, is adapted, when the same is turned, to overlie the said projecting bottom wall 17 and to have one of the teeth 28 thereon engage the rib 18 to prevent any rotary movement 65 of the locking-member which, when thus en-

gaged, will effectually hold the two clamping members together and bind the axle tightly therebetween.

When the trolley wheel accidentally slips from the line wire, it often happens that 70 the harp strikes a cross supporting-arm at a point adjacent to the periphery of the said wheel, which results in bending the upper clamping member and thus destroying the clamping action of the two members upon 75 the axle 3, as any bending or other movement of the upper member toward the lower would release the pressure of the bottom wall 17 beneath the overhanging thinner portion of the locking member, as will 80 be readily understood, and this would result in freeing the said axle in its bearings and permitting the same to rotate and to rattle. When this happens it is only necessary to introduce a suitable spanner into perforations 29 formed in the upper surface of the locking member and to turn the same in a direction to bring a thicker portion of the cam-like locking-member over the lip of the clamping member 2, when the rib 18 90 will seat in another tooth 28 and the free end of the member 2 will be forced closer to its coacting member 1 and the axle will again be securely clamped against any movement.

Should such damage to the upper clamping member 2 be not immediately detected and the trolley wheel be replaced on the wire and allowed to run, the play or slack caused by the bending of the member 2 100 might allow the rotary locking member to turn upon its axis and permit the upper clamping member to open entirely thus freeing the trolley wheel altogether, but means have been provided for preventing the accidental turning of the locking member under such circumstances, and yet permitting its rotation by means of a wrench or spanner. Said means consists of a pin 30 mounted in a socket 31 formed in the bottom wall of 105 the socket 15 and pointed on its upper end to enter between the teeth 28, a spring 32 being disposed beneath said pin to force the same upwardly into such engagement and at the same time to permit the pin to lower 110 when forced downwardly by the passage of the teeth when the locking member is rotated.

What is claimed is:—

1. A trolley harp comprising a pair of 120 axle clamping members hinged at their outer ends and bifurcated to span a trolley wheel, said members being normally spaced apart at their free ends, an extension formed on the free end of one of the members for 125 attachment to a trolley pole, and a locking member carried by said extension and mounted to rotate on an axle at right angles to the axis of the said extension, said locking member being adapted when properly 130

turned to override the free end of the other clamping member and bind the two members together to clamp the trolley axle against rotation.

- 5 2. In a trolley harp having hinged axle-clamping members, a locking means therefore comprising a swiveled locking device carried by one of the clamping members and mounted for rotation about an axis at right angles to the longitudinal center line of said clamping members, the said locking device being provided on its underside with a cam surface having a series of teeth formed thereon, an extension or lip carried by the 10 adjacent portion of the other clamping member and adapted to underride the locking device and be held in clamping relation to the other member, said lip having a rib for engagement by the teeth.
- 15 3. A clamping harp for trolley wheels having the adjacent portions of the clamping members provided with registering portions of a socket, the socket portion formed in one clamping member being of greater extent than that of the other, and having a central bore formed in the bottom wall thereof, a rib formed in the bottom wall of the portion of the socket provided on one clamping member and arranged radially of the 20 central bore, and a rotary locking member mounted in the socket and having a central bore registering with the first-named bore, and a pivot pin or screw traversing the bores, said locking device having radially disposed teeth and a peripheral cutaway portion.
- 25 4. A trolley harp comprising a pair of axle clamping members hinged at their outer ends and bifurcated to span a trolley wheel, said members having in rear of their outer ends alined seats for the reception of the 30 central bore of a trolley wheel, and being normally spaced apart toward their free ends, a socket formed partially in one member and partially in the free end of the other member, a turn-button mounted in said socket and adapted to be turned to lock the free end of said other member, said turn-button having a cam surface coöperating with means provided in the socket and tending to force 35 said members in clamping engagement with the axle.
- 40 5. A trolley harp comprising a pair of axle clamping members hinged at their outer ends and bifurcated to span a trolley wheel, said members having in rear of their outer ends alined seats for the reception of the 45 central bore of a trolley wheel, and being normally spaced apart toward their free ends, a socket formed partially in one member and partially in the free end of the other member, a turn-button mounted in said socket and adapted to be turned to lock the free end of said other member, said turn-button having a cam surface coöperating with means provided in the socket and tending to force 50 said members in clamping engagement with the axle.

55 axle of a trolley wheel, and being normally spaced apart toward their free ends, a socket formed partially in one member and partially in the free end of the other member, a turn-button mounted in said socket and adapted to be turned to lock the free end of said other member, said turn-button having a cam surface coöperating with means provided in the socket and tending to force 60 said members in clamping engagement with the axle, and a spring-actuated locking pin seated in the socket and adapted to lock the button in its adjusted position.

6. A trolley harp comprising a pair of axle clamping members hinged at their outer ends and bifurcated to span a trolley wheel, one of said members having an extension at the end remote from the hinged end for the attachment of a trolley pole, and said extension having a socket formed therein, said socket having the form of a major arc of a circle, and the other member having a socket provided at its free end which registers with 80 and completes the circle of the first-mentioned socket, said members being normally spaced apart toward their free ends, and a turn-button mounted in the first-mentioned socket and adapted to be turned to engage 85 the other socket, said turn-button having its periphery cut away to correspond with the division between the two sockets.

7. A trolley harp comprising a pair of axle clamping members hinged at their outer ends and bifurcated to span a trolley wheel, said members having in rear of their outer ends alined seats for the reception of the axle of a trolley wheel, and being normally spaced apart toward their free ends, a socket 90 formed partially in one member and partially in the free end of the other member, a turn-button mounted in said socket and adapted to be turned to lock the free end of said other member, said turn-button having a cam surface on its inner face and a series 95 of radially disposed teeth, and a rib provided on the free end of said other member, and said rib being engaged by the turn-button when the latter is turned to lock the 100 members.

In testimony that I claim the foregoing as my own I have hereto affixed my signature in the presence of two witnesses.
